(57) **CLAIM**

The ornamental design for a moisture sensor and controller, as shown and described.

DESCRIPTION

FIG. 1 is a perspective view of a moisture sensor according to our new design;

FIG. 2 is a top plan view of the moisture sensor of FIG. 1; FIG. 3 is a right side elevation of the moisture sensor of FIG. 1;

FIG. 4 is a bottom plan view of the moisture sensor of FIG. 1;

FIG. 5 is a left side elevation view of the moisture sensor of FIG. 1;

FIG. 6 is a rear elevation view of the moisture sensor of FIG. 1; and,

FIG. 7 is a front elevation view of the moisture sensor of FIG. 1.

The broken lines showing the electrical connections and electrical connection holder in FIGS. 1-4 and 6-7, as well as the broken lines showing the seam formed in the end cap in FIGS. 1-2 and 7 are shown for illustrative purposes only and form no part of the claimed design.
